GLASSWARE FORMING MACHINE

Filed March 22, 1928

FIG-1-

UNITED STATES PATENT OFFICE

STANLEY L. HEWITT, OF GLASSBORO, NEW JERSEY, ASSIGNOR TO OWENS-ILLINOIS
GLASS COMPANY, OF TOLEDO, OHIO, A CORPORATION OF OHIO

GLASSWARE-FORMING MACHINE

Application filed March 22, 1928. Serial No. 263,890.

The present invention relates to improvements in glassware forming machines, and more particularly to means for controlling movement of mold bottom plates.

In the production of hollow glassware on machines of the type to which the present invention relates, the finish molds in which the articles assume their final shape are opened at a predetermined station at which the mold bottom tilts to a position permitting the ware to drop by gravity into a chute or joints from which the ware passes to leer pans. In double mold operation, that is, operation of molds having two ware shaping cavities cooperating with a pair of bottom plates of ordinary construction, more or less difficulty is encountered in so ejecting the articles that they fall into corresponding chutes with accuracy. This objection arises from the employment of the so-called "floating bottom plates" in which the plates are free to move relative to the bottom plate holder when the finish mold sections close about said plates and again when the sections separate to permit ejection of the finished ware. This latter movement has proven objectionable in that the timing of the ware ejecting operation cannot be relied upon to effect proper delivery of the ware into the chutes or other ware handling mechanism. Obviously, this is due to the fact that there is no uniformity of spacing between the plates and chutes when the former are subject to varying degrees of lateral movement.

An object of the present invention is to provide means to minimize, if not entirely eliminate, lateral movement of the bottom plates relative to the bottom plate holder after the finish mold sections have opened. Thus, tilting of the bottom plates and their holder will not cause or permit the bottom plates to move laterally from the positions occupied at the time the mold opens. Because of this arrangement, the articles are retained in proper position relative to the bottom plate holder until they have reached the point at which they should be allowed to fall from said plates into the chutes.

Another object of the invention is to

provide yielding means which readily permits alignment of the bottom plates with the mold cavities as the mold closes about said plates and at other times creates sufficient frictional contact between the bottom plates and their holder to prevent lateral shifting of said plates, irrespective of the angular position of the holder.

Other objects will be apparent hereinafter.

In the accompanying drawings:

Fig. 1 is a sectional elevation illustrating the present invention in connection with a finishing mold having two cavities therein.

Fig. 2 is a detail transverse sectional view taken substantially along the line II--II of Fig. 1.

Fig. 3 is a detail sectional view illustrating the manner in which the present invention operates to prevent lateral shifting of the bottom plates upon the bottom plate holder.

In the drawings, the portable finish mold 5 is formed with two mold cavities 6, said mold being supported and alternately opened and closed in any approved manner. The upper end of this mold 5 cooperates with a portable neck mold 7. The lower end of the mold 5 cooperates with bottom plates 8 and a bottom plate holder 9 carried by a frame 10 which is tiltingly supported on a track 11, a roller 12 being interposed between said frame 10 and track 11 for obvious reasons.

The bottom plate holder 9 comprises an open frame 13 carrying a centrally disposed upwardly opening cup or well 14, said cup being connected to the frame 13 by radial ribs 15. This cup 14 and a horizontal flange 16 extending inwardly from the lower end of the frame 13, support a supplemental frame 17, comprising a peripheral portion 18 snugly fitting into the open frame 13 (Fig. 1) and carrying a centrally disposed depending cylinder 19 which projects into said cup or well 14.

This cylinder head 21 is formed with a radial flange 20 which rests upon the upper end of the cup 14. The head 21 of the cylinder 19 is formed with an axial opening 22 providing communication between the in-

terior of said cylinder and a transverse channel 23 in a reinforcing cross bar 24 which is integrally formed with the cylinder 19 and the peripheral portion 18 of the supplemental frame 17. A spring pressed detent 25 carried by the cup 14 removably secures the frames together in the fashion shown in Figs. 1 and 3.

The bottom plates 8 carry eye screws 26 which extend downwardly into recesses 27 into which the opposite ends of said transverse channel 23 open. A connector bar 28 is disposed in said channel 23 and has its ends projecting loosely through said eye screws 26. A screw 29 or some other similar element is fixed to the connector bar 28 and extends downwardly through the axial opening 22 in the cylinder head 21 for connection to one end of a coil spring 30 in the cylinder 19. The other end of said coil spring is suitably connected to a cross pin 31 or the like, fixed to the lower portion of said cylinder. The coil spring 30 yieldingly holds the bottom plates 8 in contact with the upper surface of the auxiliary frame unit 18 during the periods of time that the finish molds 5 are opened.

The lower portions of the walls of the mold cavities 6 are formed with inclined annular shoulders 32 which, when the mold 5 closes, engage downwardly facing inclined annular shoulders 33 on the mold bottom plates 8. This construction insures accurate alignment of the mold cavities and bottom plates when the mold closes.

The operation may be stated as follows:

Prior to closing of the mold 5 about parisons depending from the neck mold 7, the coil spring 30 exerts such downward pull on the elements connecting said spring and the bottom plates that the latter are frictionally engaged with the upper surfaces of the bottom plate holder (Fig. 3) under such pressure that tilting of said holder will not result in lateral movement of said plates relative to each other or the holder. Thus, these plates are at all times so accurately positioned relative to the holder and mold 5 that when the mold closes about said plates, the latter are subjected only to a slight vertical movement which lifts them to substantially the position shown in Fig. 1. It is evident that no lateral movement on the part of the bottom plates will be necessary to align them with the mold cavities. After the parisons have been blown to the final form of the articles (Fig. 1) and the mold is approaching the ware ejecting station, both the neck and finish molds open, and knock-out arms (not shown) assist in supporting the articles upon the bottom plates 8 until the ejecting station has been reached. Simultaneously with opening of the finish mold, the spring 30 operates to snugly inter-

holder so that when the holder is tilted (Fig. 3) to eject the articles, the relative positions of the bottom plates to each other or to the holder are not changed. Thus, interference with orderly ejection of the articles is avoided, with the result that said articles are always deposited in the proper chutes or other ware handling means.

Modifications may be resorted to within the spirit and scope of the appended claims.

What I claim is:

1. In combination, a tilttable bottom plate holder comprising a pair of open frames nested one within the other, means separably interconnecting said frames, a pair of bottom plates, and means including a single spring providing a yielding connection between said bottom plates and the inner frame operating at times to effect a sufficient degree of frictional engagement between said plates and holder to prevent relative lateral movement between said elements.

2. In combination, a tilttable bottom plate holder comprising a pair of open frames nested one within the other, means separably interconnecting said frames, a pair of bottom plates, and means providing a yielding connection between said bottom plates and the inner frame operating at times to effect a sufficient degree of frictional engagement between said plates and holder to prevent relative lateral movement between said elements, said connection including a cross bar loosely interconnecting said bottom plates and a coil spring having connection at one end to an intermediate portion of said bar and at its other end to one of said frames.

3. In combination, a tilttable bottom plate holder comprising a pair of open frames nested one within the other, means separably interconnecting said frames, a pair of bottom plates, means providing a yielding connection between said bottom plates and the inner frame operating at times to effect a sufficient degree of frictional engagement between said plates and holder to prevent relative lateral movement between said elements, said connection comprising a cross bar positioned below said bottom plates and having its opposite ends loosely connected thereto, and yielding means exerting downward pressure on said cross bar to cause frictional engagement between said plates and holder at times preventing relative lateral movement between said holder and plates.

4. In a machine for forming glass articles, the combination of a plural cavity mold, mold bottom plates individual to the mold cavities, a holder on which said bottom plates are supported, said plates being free for universal lateral movement on said holder to permit accurate alignment of the bottom plates with the mold cavities, and yielding means including a single spring for

frictionally opposing lateral movement of both said plates.

5. In a machine for forming glass articles, the combination of a plural cavity mold, mold bottom plates individual to the mold cavities, a holder on which said plates are mounted, said plates being individually movable laterally on the holder for aligning them with the mold cavities, said holder and bottom plates being movable from a horizontally disposed to an inclined position for discharging articles when the mold is opened, and a single spring for frictionally holding both said plates against lateral movement while the holder is in discharging position.

6. In combination, a plural cavity mold, a tiltable bottom plate holder comprising a pair of open frames nested one within the other, the inner frame having a plurality of openings adapted for register with the cavities of the mold at times, a plurality of bottom plates mounted for multi-directional movement on the inner frame, and means including a single spring carried by the inner frame and operating at times to effect such frictional engagement between the plates and inner frame that relative lateral movement between the plates and between the plates and frame is prevented.

Signed at Glassboro, in the county of Gloucester and State of New Jersey, this 16th day of February, 1928.

STANLEY L. HEWITT.
